UNITED STATES PATENT OFFICE.

WILHELM C. DE WENDT, OF NEW ORLEANS, LOUISIANA.

COMBINED WRITING-SHEET AND ENVELOP.

1,271,862.

Specification of Letters Patent.

Patented July 9, 1918.

Application filed November 1, 1916. Serial No. 128,908.

To all whom it may concern:

Be it known that I, WILHELM C. DE WENDT, a citizen of the Republic of Haiti, residing in the city of New Orleans, parish 5 of Orleans, State of Louisiana, have invented certain new and useful Improvements in Combined Writing-Sheets and Envelops, of which the following is a specification.

10 My invention relates to combined writing sheets and envelops, and its primary object resides in the provision of a single sheet of writing paper, which may be conveniently folded and closed for transmission through 15 the mails to accommodate either first class or third class mail regulations, as desired.

A further object is to combine a sheet of writing paper and envelop in such a manner that both the face of the letter and the face 20 of the envelop shall be upon the same side of the paper, and may be printed at one impression, saving thereby double printing press work.

25 A further object is to provide a writing sheet and envelop combined as may be conveniently desired, which will provide ready means for inspection as third class mail matter, when mailed as such, and which shall have the general outside appearance of 30 first class mail matter.

A further object is to provide a writing sheet and envelop combined, which shall require less paper than when constructed separately, and which will, in consequence 35 cost less for paper; be lighter in weight; and thus permit the mailing of more sheets in each letter at the minimum rate for postage.

40 A further object is to provide a writing sheet and envelop combined, wherein the name and address written in the usual space on the letter head may be seen, after the envelop is closed, through a suitable opening in the envelop portion, thereby avoiding 45 double writing of such name and address, and the mistake of mailing a letter in an envelop addressed to a different person, as often occurs as at present practised.

50 My invention consists of the improved construction of a combined writing sheet and envelop illustrated in the accompanying drawings, in the various views of which like parts are similarly designated, and in which—

55 Figure 1 represents my invention as adapted to a writing sheet of the size of the

usual business letter head, and the number six envelop, showing the face of the envelop and letter head.

Fig. 2 represents the front face view of 60 the same writing sheet and envelop after being folded to the third position.

Fig. 3 represents the same writing sheet and envelop completely folded, the gummed flaps ready for closing either by tucking in 65 or sealing as desired.

In Fig. 1 of the drawings, I have preferably shown my invention as adapted to the usual form and size of business letters, combined with the usual number six size of envelop, the whole being formed from a single sheet of paper of the desired weight and color, the form being designed for folding and sealing as hereinafter more particularly described. 75

The front of the envelop portion is indicated by the numeral 1, which is preferably provided with an opening 10, to expose the name and address of the correspondent, and the end flaps 7 and 9, and the bottom flap 80 8, for closing and sealing as hereinafter explained. The opening 10 may be covered with transparent material, if desired, or it may be omitted entirely, and the name and address written thereon in the usual manner when preferred. The flaps 7, 8, and 9 85 are gummed on the reverse side with adhesive for use in sealing the letter. The adhesive may be omitted from the flaps Nos. 7 and 9 when used for third class mail 90 matter in the manner hereinafter described.

As shown in Fig. 1, I have so arranged my invention that the face of the envelop and the face of the writing sheet are upon the same side of the paper. Thus it will 95 be seen that all printing of letter heads, return cards, etc., may be printed upon both the writing sheet and envelop at one and the same impression, thereby saving the extra press work usual with other combined 100 writing sheets and envelops, and with writing sheets and envelops detached. It will further be seen that the top of the envelop and the top of the writing sheet are in the same direction, and all printing is readable 105 without turning the sheet, and all writing may be done upon both the writing sheet and envelop at one insertion in the typewriter, without removing and reversing as is the case with others. 110

After the desired printed or written matter has been placed upon the writing sheet,

it is folded for mailing as follows: first, fold the top one third of the writing sheet backward approximately along the dotted line 10 against the rear of the portion 4; second, 5 fold the portions 4 and 5 forward approximately along the dotted line 11, against the front of the portion 3, when the partially folded writing sheet and envelop will be in the form shown in Fig. 2; third, fold the 10 portion shown as 6 backward, along the dotted line 12, against the rear of the folded portions; fourth, fold the folded portion backward along the dotted line 13 against the rear of the portion 2; fifth, fold backward again along the dotted line 14, against the rear of the front of the envelop 1. The 15 folded writing sheet and envelop will then resemble the illustration shown in Fig. 3, the name and address on the letter head appearing immediately beneath the opening in the envelop front 1.

To seal the said letter for first class mail, the three flaps 7, 8, and 9 are moistened, and are turned backward, and pressed down 20 against the rear of the folded letter, until the gum adheres, thus sealing all open edges of the letter.

If, instead, it is desired to close said letter for mailing as third class mail matter, the 30 ends 7 and 9 are folded backward, and tucked in between the edges of parts 2 and 3 adjacent to them. The flap 8 may likewise be folded backward, and tucked in between the folded edges of parts 3 and 4, or if preferred, it may be moistened, and pressed down against the rear side of the folded letter, and gummed fast, for by removing the 35 end flap 9 from its position between the portions 2 and 3, all sides of the inclosed matter may be inspected without other opening of said envelop.

It will be apparent that the parts 1 and 2 above may be the full width of the writing sheet, and fold to the size of large legal sized 40 envelop without departing from the spirit of my invention; it will further be apparent that the part 2 may be full width of the writing sheet, and used for printed or written matter. It will further be apparent that 45 either single or double sheet note paper size may be used in place of that shown and used

and folded in approximately the same manner without departing from the spirit of my said invention. It may also seem best to vary the size or shape of the flaps as shown, 55 which will not materially vary from the spirit of my said invention.

Having thus described my invention, what I claim and desire to secure by Letters Patent is the following:

A combined letter sheet and envelop comprising a substantially rectangular writing sheet provided at one end with a relatively narrow intermediate connecting portion laterally reduced at one side and extending from and arranged in flush relation with the longitudinal edge at the other side of the letter sheet and terminating short of one of the longitudinal edges of the said writing sheet to form a relatively narrow laterally projecting portion of a width materially less than the intermediate connecting portion, said letter sheet being folded on transverse lines spaced apart substantially the width of the intermediate connecting portion so as to permit the folded letter sheet to overlie the said intermediate portion, the relatively narrow laterally extending portion of the writing sheet being folded longitudinally of the latter into the area of the intermediate connecting portion and over the same, said intermediate connecting portion constituting the back of the envelop and the envelop portion being located at the outer end of the intermediate connecting portion and provided with end and bottom flaps foldable around the writing sheet and the said intermediate connecting portion when the same are folded against the inner face of the envelop portion, the front face of the writing sheet and the front face of the envelop portion being located at the same face of the paper and the said envelop portion having an opening adapted to expose an address on the terminal portion of the writing sheet.

In testimony whereof I have hereunto affixed my signature in the presence of two witnesses.

WILHELM C. DE WENDT.
